UNITED STATES PATENT OFFICE.

JAMES J. HARKINS, OF PITTSBURG, PENNSYLVANIA.

HEATING-FURNACE.

No. 906,416.

Specification of Letters Patent.

Patented Dec. 8, 1908.

Application filed March 8, 1907. Serial No. 361,401.

To all whom it may concern:

Be it known that I, JAMES J. HARKINS, a resident of Pittsburg, in the county of Allegheny and State of Pennsylvania, have invented a new and useful Improvement in Heating-Furnaces; and I do declare the following to be a full, clear, and exact description thereof.

My invention relates to heating furnaces and has special reference to what are known as continuous heating furnaces for the heating of billets, blooms, slabs, etc.

The object of my invention is to provide a heating furnace which will be cheap, simple and efficient in its construction and operation, in which the metal can be heated in less time and with less labor than in the ordinary class of these furnaces, as well as one which will thereby cheapen the cost of production and will facilitate repairs.

My invention consists, generally stated, in the novel arrangement, construction and combination of parts, as hereinafter more specifically set forth and described and particularly pointed out in the claims.

To enable others skilled in the art to which my invention appertains to construct and use my invention, I will describe the same more fully referring to the accompanying drawings, in which—

Figure 1 is a vertical central section of my improved apparatus for heating furnaces and showing a section of the furnace through the gas flues. Fig. 2 is a horizontal section of the furnace on the line 2—2 Fig. 1 looking in the direction of the arrows and showing some of the parts broken away. Fig. 3 is a vertical central section of the furnace, taken at right angle to Fig. 1 on the line 3—3 Fig. 2 and showing some of the parts broken away and in full lines. Figs. 4 and 5 are detail views.

Like symbols of reference herein indicate like parts in each of the figures of the drawing.

As shown in the drawings the general form or superstructure of the furnace 1 is the same as the usual form of a regenerative or recuperative furnace, as shown, and within the heating chamber 2 and running parallel with the sides of the furnace are the division walls 3, which are provided with the transverse archways 4 to allow the charge of metal within the furnace 1 to pass under the same in its movement within said furnace as hereinafter described. The furnace 1 being of the usual form is provided with the gas flues

a which lead from the gas generating chambers *b* and into the chamber 2 with the air flues *c* which lead from the usual source of supply into said chamber alongside of said flues *a*.

Within the center of the furnace 1 is the table, hearth or bottom 5 for the charge of metal and this bottom is circular and revolvable and is composed of the fire-brick hearth portion 6 which is provided with the built-up annular portions 7 extending up from the same with the outer one being downwardly inclined towards the center of the furnace. Between these portions 7 is placed a sandbed 7' having its upper face formed concave between the portions 7 and its inner side to form a recessed or corrugated face and such bottom 5 is supported on a plate 5' which is connected to the angle-bars 6' at its sides and within the inner and outer portions 7. The bottom 5 is provided with the central opening 10' through the same and within said opening the central furnace portion 10 is built and supported on a central column 11. The column 11 is preferably formed of hollow cast iron and extending loosely around the same is a movable sleeve 11'. Arms 12 extend radially out from a loose sleeve 13' on the column 11 and are attached thereto, and these arms have the gear wheel or face 12' at outer ends of the same, while such arms are also connected to the plate 5' of the bottom 5 through the vertically disposed plates 5".

On the under side of the arms 12 is a track 13 for engaging with anti-friction rollers 14 which are mounted upon one end of the pins 15, while the opposite ends of these pins are flattened and secured between plates 16 in any suitable manner. On the upper and lower ends of the plates 16 are the flanged wheels 17 which are mounted on pins 18 passing through said plates and thereby form a movable carriage 19 to carry the furnace bottom 5 by said wheels engaging with the columns 20. A clevis hook 21 is connected to the upper end of the carriage 19 and to said hook is attached a chain 22 for passing over a sheave 23 mounted on the columns 20 and carrying at its lower end a weight 24. The columns 20 are preferably formed of two channel bars and the plates 16 of the movable carriage 19 pass between them so that the rollers 17 will bear against each side of said columns and thereby properly support the bottom 5 by said carriage.

The weight 24 will act to support the car-

riage 19 which in turn supports the bottom 5 through the rollers 14 and the columns 20 act as a guide and support for the movable carriage 19, as well as the sheave 23 and four of these carriages are shown around the circumference of said bottom, but it is evident that any number can be used.

Engaging with the gear wheel 12' is the pinion 25 which is keyed by a feather around 10 a vertical shaft 26 and this shaft has a worm wheel 27 at its lower end for being engaged by a worm 28 mounted on a horizontal shaft 29. Mounted on the shaft 29 is a gear-wheel 30 which meshes with a pinion 31 mounted 15 on a shaft 32 which carries a gear-wheel 33 meshing with a pinion 34 on the armature shaft 35 of a motor 36.

Fulcrumed at 37 on a bearing 38 supported by a standard 39 is a vibrating lever 40 which 20 is formed of two bars and spaced far enough to allow of the fulcrum 37 being placed between them and at one end of said lever are secured the straps 41 which are connected at their free ends with pins 42 extending out 25 from the annular seat 43 formed in the movable sleeve 11 through slotted holes 44 in said ends of said straps. A vertical screw-rod 45 is pivotally connected at its lower end to links 46 which are pivotally connected to 30 said lever 40 and the upper end of said rod passes through a stand 47 and is screw threadedly connected within a worm-wheel 48 secured on said stand by means of a bar 49 through which said rod loosely passes. A 35 worm 50 is mounted on a shaft 51 secured on the stand 47 and such shaft is provided with two crank levers 52 for raising and lowering the rod 45.

The use and operation of my improved apparatus for heating furnaces is as follows:— 40 When power is applied to the motor 36 the shaft 35 will be revolved which will act to revolve the shaft 29 through the gears 33 and 34, shaft 32 and gears 30 and 31, and as 45 such shaft 29 is thus revolved the shaft 26 will be revolved through the worm 28 and its wheel 27, which will also revolve the bottom 5 through the pinion 25 on the shaft 26 engaging with the gear-wheel 12' on said bottom. During this revolving of the bottom 5 the billets, blooms or slabs, etc., such 50 as A are charged into the chamber 2 of the furnace 1 through the opening B in said furnace in any suitable manner, so that they 55 will lie on the outer and intermediate portions 7 on said bottom as shown in Figs. 2 and 3, to allow for the circulation of the heat under the same through the spaces formed by the upper concave face on the 60 sand bed 7', and such charging can be accomplished automatically or otherwise by any suitable mechanism, as through the medium of an automatic sprocket mechanism shown diagrammatically in Fig. 3 at C. This 65 mechanism C is composed of a sprocket

chain 53 which passes through the opening B, and over the sprocket wheels 54, the inner of which is located within said opening and chamber 2 over the bottom 5, and such chain is provided with fingers 55 for engaging with the metal A to be carried into said chamber from the table 56 to be heated. The chain 53 can be operated from the shaft 29 by means of any suitable mechanism such as the pinion 57 on said shaft meshing 70 with a gear-wheel 58 on a shaft 59 which is provided with a sprocket wheel 60 having a sprocket chain 61 passing around the same and around a like wheel 62 on the shaft 63 carrying the outer sprocket wheel 54.

As the bottom 5 in the furnace 1 is revolved the metal A charged onto said bottom is heated within the chamber 2 and when such metal reaches the opening D in the furnace 1 adjacent to the opening C 80 therein it can be discharged in any suitable manner and automatically if desired, as by means of a tilting bar 64 extending into said chamber through said opening D and operated by any suitable mechanism connected to the 85 mechanism for charging the metal into the furnace or other mechanism, as is desired.

The revolving bottom 5 of the furnace 1 is counterbalanced through the weight 24 when about one-half of a charge of metal is 90 within the chamber 2 of said furnace, so that when a full charge is within said furnace some upward compression may be placed upon the rod 45, and when it is desired to lower the bottom 5 the operators can turn 100 the levers 52 in the proper direction which will act to raise the rod 45 through the medium of the worm 50 and its wheel 48 and draw up the outer end of the tilting lever 40 and lower its inner end, so that this end will 105 carry down the sleeve 11' on the column 11 and with it said bottom. As the bottom 5 is thus lowered the gear-wheel 12 on the same will be lowered therewith, as well as the pinion 25 on the shaft 26 and in the 110 raising of said bottom by a reverse movement of the cranks 52 the movable sleeve 11' and said bottom will be raised through the means above described, so that the pinion 25 will be raised with the bottom and through 115 its meshing with the wheel 12 permit said bottom to revolve when power is applied from the motor 36 for its operations. During the raising and lowering of the bottom 5 the carriage 19 will be moved on the columns 120 20 through the weights 24 in the same direction with the said bottom and with the plates 16 moving within the said columns, so that in such movement of the bottom the rollers 14 on said carriage will be in engagement with and support said bottom.

Various modifications and changes in the design, construction and operation of the various parts of my improved apparatus for heating furnaces may be resorted to without 125 130 135 140 145 150 155 160 165 170 175 180

departing from the spirit of the invention or sacrificing any of its advantages.

It will thus be seen that my improved apparatus for heating furnaces can be applied to any form of a heating furnace and with the use of charging and discharging devices on the same these operations can be performed continuously and automatically and the whole charge may be drawn and replaced in a very short space of time if it is found necessary to do so, while these operations can be carried on at one side of the furnace and adjacent to each other, thus saving heat and reducing oxidation by shutting off large quantities of cold air.

The devices are easily and conveniently operated and will not be brought into contact with the heat of the furnace, while they can be water-cooled if desired. They will not get out of order and will be durable and strong, and at the same time they will be positive and easy to operate at all times and without the employment of complicated mechanism.

What I claim as my invention, and desire to secure by Letters Patent, is:—

1. A heating furnace having a heating chamber, a column, a revolving bottom within said chamber, means including a weight for supporting the outer portion of said bottom in all its positions a movable sleeve on said column for carrying said bottom, and a screw operated tilting lever or bar connected to said sleeve for raising and lowering said bottom.

2. A heating furnace having a heating chamber, a column, a revolving bottom within said chamber, means including a weight for supporting the outer portion of said bottom in all its positions a movable sleeve on said column for carrying said bottom, a tilting lever or bar connected to said sleeve, and a screw-rod loosely connected to said bar for raising and lowering said bottom.

3. A heating furnace having a heating chamber, a column, a revolving bottom within said chamber, means including a weight for supporting the outer portion of said bottom in all its positions a movable sleeve on said column for carrying said bottom, a tilting lever or bar connected to said sleeve, a rod connected to said bar, and means con-

nected to said rod for tilting said bar in the raising and lowering of said bottom.

4. A heating furnace having a heating chamber, a column, a revolving bottom within said chamber, means including a weight for supporting the outer portion of said bottom in all its positions a movable sleeve on said column for carrying said bottom, a tilting lever bar connected to said sleeve, a rod connected to said bar, a worm-wheel screw-threadedly connected to said rod, and a worm engaging with said wheel for moving said rod to tilt said bar in the raising and lowering of said bottom.

5. A heating furnace having a heating chamber, and a revolving circular bottom within said chamber having its upper face provided with annular corrugations extending up from and around the same for the free circulation of heat around the metal placed thereon to be heated.

6. A heating furnace having a heating chamber, a revolving bottom within said chamber having its upper face provided with corrugations extending up from the same for the circulation of heat around the metal placed thereon to be heated, and a sand bed within the recesses formed by said corrugations.

7. A heating furnace having a heating chamber, a revolving bottom within said chamber having upwardly extending portions on its upper face to form corrugations, and a sand bed on said face and within the recesses formed between said portions and its inner side.

8. A heating furnace having a heating chamber, a revolving bottom within said chamber, upwardly extending portions at its outer edge and intermediate thereof to form corrugations and said outer portion being inclined downwardly toward the center of the furnace, and a sand-bed on said face and within the recesses formed between said portions and its inner side.

In testimony whereof I have signed my name to this specification in the presence of two subscribing witnesses.

JAMES J. HARKINS. [L. S.]
